UNITED STATES PATENT OFFICE.

CARL SIGFRID NYBERG, OF SÖDERTELJE, SWEDEN.

PACKETING-MACHINE.

1,088,791.

Specification of Letters Patent.

Patented Mar. 3, 1914.

Application filed February 26, 1910. Serial No. 546,109.

To all whom it may concern:

Be it known that I, CARL SIGFRID NYBERG, a subject of the King of Sweden, and resident of 7 Rådhustgatan, Södertelje, in the 5 Kingdom of Sweden, engineer, have invented certain new and useful Improvements in Packeting-Machines, of which the following is a specification, reference being made to the accompanying drawings.

10 The present invention relates to devices in packeting machines having for its purpose to accomplish the folding at the ends of the packet of the paper wrapped around it in the machine and having been folded 15 over one edge at each of its ends, and thereupon to paste the flaps at the ends, and if desired, also to label the packet.

A machine carried out according to the 20 present invention is shown on the accompanying drawings in which—

Figure 1 is a front elevation, Fig. 2 an end elevation and Fig. 3 a plan of the machine. Fig. 4 is a detail.

The device for making the first folding of 25 the wrapper at the ends of the packet is assumed to consist of folding plates, jaws or the like, 1, belonging to the packeting machine and which are carried by displaceable rods 2. Between said jaws is shown a 30 square packet 3 (containing for instance matchboxes) over the ends of which the jaws have descended and thereby carried out the said first folding down of the wrapper. The packet 3 is assumed to be in the 35 position in the machine where it has been provided with the wrapper and has been caught between the jaws 1, and from which place one packet after the other is moved forward (to the right in Figs. 1 and 3) by 40 the said jaws toward the devices which form the object of this invention. In Figs. 1 and 3 is shown a number of packets thus moved, designated with the numbers 4, 5, 6, 7 and 8, of which the one after the other is acted 45 upon by a device adjacent to each packet either while being moved from one position to another or while at rest in a certain position.

When the rods 2 are displaced in order to 50 move forward the packet 3, the said rods

move so far as to cause the packet to assume the position which in the drawing is assumed by packet 4. Above the latter there is a presser foot 9, which, as soon as the packet has assumed the position in which 55 packet 4 lies, descends on and holds fast the latter, whereupon the jaws 1 first ascend straight up and then move back to fetch the next packet. The packet which has been introduced under the presser foot, 9, and 60 which has the wrapper folded only at one place at each end has thus the wrapper projecting from the side edges 10 and 11 as well as from the under edge 12. While the next packet 3 is being moved forward to the 65 position of packet 4, folders 13, which are adjustably secured to the rods 2 in front of the jaws 1, will strike the wrapper projecting from the said edges 10 of the packet 4, so that the said wrapper will be folded over 70 the said edges. The folders 13, whose front edges are suitably rounded, will then slide up on the ends of the packet 4, until a plate 14 which is placed at the back of each folder and extends somewhat into the path of the 75 packets, strikes against the back of the packet, whereupon the latter is moved forward till it assumes the position of packet 5, whereby the latter as well as all the packets in front of the same are moved by the 80 packet 4 a distance equal to the breadth of a packet in the direction of the movement. In order that the packet 4 may rest securely in its position under the presser foot 9, while the folders 13 slide on its ends, the 85 presser foot is at the front edge provided with a low shoulder 15, against which the upper front edge of the packet rests. While the folders 13 are sliding on the ends of the packet, the lower ends of the folders are a 90 little above the lower edge of the packet, in order that the wrapper along this edge may not be injured by the folders. As soon, however, as the plates 14 have come against the back of the packet, and the folding over 95 the edges 10 has taken place, the folders 13 descend with their lower ends completely down on the underlying wrapper, whereby the latter is folded sharply at the under edges 12 of the packet. In order that the 100

shoulder 15 may not hinder the packet 4 when it is being moved forward, the presser foot 9 is lifted slightly, as soon as the forward movement is to begin. The packet 4 is then first moved forward alone by the plates 14, until it comes against the packet 5, whereupon all the packets in front of packet 4 are moved forward by the same. The forward movement ceases when the packet 4 reaches the position assumed by the packet 5 in the drawing and at this point packet 3 is evidently in the position of packet 4 under the presser foot 9. When the jaws 1 and the folders 13 thereafter ascend in order to move backward to the following packet, the packet 5 is held down on the table by a presser foot 16, which extends to such a distance forward, that the packets 6, 7 and 8 also lie under it.

When the folders 13 have folded the wrapper around the upright edges 10, the wrapper at the ends of the packet is then folded in the manner shown in packet 5 in Fig. 3. The next folding which is to be done is the folding around the upright edges 11, and it is performed with the aid of folders 17, each of which consists of an angular plate, connected with an arm 18, which at the back is adjustably connected with a pin 19, so that the arm can be adjusted more or less close to the packets. After the adjustment each arm 18 may turn around its pin 19, and this latter is carried by a sleeve 20, which is rotatably mounted on a pin 21, the longitudinal direction of which is at right angles to the longitudinal direction of the pin 19, in consequence of which the folders 17 can move to and from the packet which is between the same as well as up and down.

In order to hold the folders 17 against the packet lying between them, each arm 18 is provided with an upright pin 22, which pins are connected by means of a spring 23, which pulls the folders toward one another. When the packet 5 stops in the position shown in the drawing, its front side is about in a line with the rear sides of the folders 17, so that, when the packet 5 is moved forward by the packet 4 which lies behind it, the wrapper is folded along the upright edges 11.

The folders 17, the upright corners of which are suitably rounded, as shown in Fig. 3, are kept slightly lifted during the time required for the packet to be moved forward to the place assumed on the drawing by packet 6, whereupon the folders descend, so that a sharp fold is formed at the under edge 12, and the folders have their under sides resting on the flap 24 which the wrapper now forms at each end of the packet. When the next packet 4 pushes forward the packets in front of the same, the packet 6 is pushed forward to the place assumed in the drawing by the packet 7, in which position each of

its flaps 24 arrives under a pasting roller 25 in order to be supplied with paste. The pasting roller 25 enters with a part of its circumference into a corresponding opening at the lower end of a paste magazine 26, Fig. 4, and is fixed to a shaft 27, which is provided with a ratchet wheel 28 or the like, with which engages a spring 29, a pawl, or the like. The magazines 26, which are movable up and down, descend with their rollers 25 on the flaps 24, as soon as the packet has reached the position assumed in the drawing by packet 7. During the downward movement of the magazines each of the ratchet wheels 28, and thus also the rollers 25 are made to rotate by the stationary spring 29, and thus the rollers carry on their circumferences paste from the magazines so that when they come in contact with the underlying flaps 24 these will be provided with paste. When the packet 7 then is moved to the position assumed in the drawing by the packet 8, each of the flaps 24 slides up on and is turned up toward and pressed against the end of the packet by a plowshare-shaped plate such as is used for the same purpose in previously known packeting machines.

As to the above named movable parts of the machine, the jaws 1 and the folders 13 are set in motion by parts of the packeting machine which do not belong to this invention. As to the other movable parts, the presser foot 9 is fixed to the end of an upright rod 30, and the presser foot 16 to a similar rod 31. The rod 30 is movable up and down in a sleeve 32, which is firmly united or in one piece with another sleeve 33, in which the rod 31 is movable up and down. The last named sleeve 33 is integral with or forms part of a cross piece 34, which at each end is attached to and carried by an upright rod 35, which is movable longitudinally in the frame of the machine. At the lower ends the rods 35 are connected by means of another cross piece 36, which carries a roller 37, which rests against a cam 38 on the driving shaft 39 of the machine, whereby the rods 35, the cross piece 34 and the sleeves 38 and 33 are set in an up and down motion. This motion is so timed that the presser feet 9 and 16 when required will be lifted by the sleeves 32 and 33 striking against the collars 40 and 41 fixed to the rods 30 and 31. In order to regulate the pressure with which the feet 9 and 16 press against the underlying packets, the rods 30 and 31 are at their upper ends provided each with a cup 42, 43, in which shot or the like can be introduced and removed. The above named up and down motion of the folders 17 is brought about by each of the folders being provided with a projection 44, which extends in over the presser foot 16 and is there provided with an adjusting screw 45, which has to be

so adjusted that the folder 17 is lifted to the desired height by the presser foot 16. The required up and down motion of the magazines 26 is brought about by their being carried by arms 46, which project from or are attached to the cross piece 34 or the rods 35. In order to prevent the presser feet from turning, there is attached to each rod, 30 and 31, an arm 47, the end of which has the form 10 of a fork 48, in which the other one of the rods 30 and 31 lies.

In order to provide the ready folded packets with the usual labels, one of which is fastened on that side of the packet where is the 15 end of the wrapper, and one on each end of the packet over the folds of the wrapper, there is in a suitable place above the row of ready folded packets lying on the machine table a paste magazine 49 and on each 20 side of the row a paste magazine 50. These magazines may be arranged in some previously known way so as, when they come in contact with the surface of the packet to be pasted, to supply the same with paste. 25 The paste magazine 49 is carried by an arm 51 extending from the cross piece 34, whereby the magazine is moved by the latter to and from the underlying packet. The two magazines 50, on the other hand, are approached to and removed from the row of 30 packets by means of rods 52 of which there is one on each side of the machine table. Each rod 52 carries at a suitable place the magazine 50 which is on its side of the table 35 and is at either end provided with a pin 53, which passes into a corresponding recess in the machine table, so that the rods 52 can be moved to and from the table. The rods 52 are pulled toward the machine table by 40 springs 54 connecting the same, while the device for drawing the rods apart consists of cam surfaces 55, one of which is at either end of each of the rods 52, and two of which are carried by the rods 35 and the two other 45 by a couple of rods 56, which at their upper ends are connected by means of a cross piece 57, and, like the rods 35, acted upon by the driving shaft and movable up and down in the machine frame. Against the cam surfaces 50 faces 55 rest rollers 58, which are fixed to the ends of the rods 52 and pressed by the springs 54 against the cam surfaces, so that, when the rods 35 and 56 move up and down, each rod 52 will move to and from the machine table and thus move the paste magazine 50 fixed to it to and from the opposite packet. In order afterward to fix the labels on the packets where the same have been provided with paste, there is above the row 55 of packets a label magazine 59, which is carried by the cross piece 57 and moved by the rods 56 to and from the underlying packet, whereby the undermost label in the magazine is fixed to the packet. For labeling the ends

of the packets, there is fixed on each of the rods 52 a label magazine 60, which on the inward motion of the rod fixes a label on the packet opposite the same. The now necessary pressing of the labels is done by brushes or the like, of which one brush 61 is carried 70 by the cross piece 57 and one brush 62 by each of the rods 52. It is obvious that all these brushes are moved to and from the packets opposite the same.

Having now described my invention, what 75 I claim as new and desire to secure by Letters Patent is:

1. In a wrapping or packeting machine, the combination with means for feeding a partially wrapped packet into the machine, 80 of folders adapted to coöperate with the end folds of the wrapper to fold the same, means carried by and moving with said folders for feeding the packet forward after the folding operation, and means for lifting both the 85 folders and the second named feeding means during their return movement.

2. In a wrapping or packeting machine, the combination with means for feeding a 90 partially wrapped packet into the machine, of folders adapted to coöperate with the end folds of the wrapper to fold the same, a presser foot adapted to engage one face of the packet after certain of the end folds have been folded, and means on said folders 95 adapted to coöperate with the presser foot for lifting and lowering the folders as said presser foot is raised and lowered.

3. In a wrapping or packeting machine, the combination with means for feeding a 100 partially wrapped packet into the machine, of folders adapted to coöperate with the end folds of the wrapper to fold the same, a cross piece or member extending transversely of the machine, a vertical rod guided within 105 said cross piece or member, a presser foot carried by said vertical rod and capable of engaging one face of the packets passing through the machine, and means on said vertical rod adapted to coöperate with the 110 cross piece for lifting the presser foot when said cross piece is moved in an upward direction.

4. In a wrapping or packeting machine, the combination with means for feeding a 115 partially wrapped packet into the machine, of folders adapted to coöperate with the end folds of the wrapper to fold the same, a presser foot adapted to engage one face of the packet, a projection on the folders adapted 120 to overhang the presser foot, an adjusting screw carried by said projection, and means for raising the presser foot to lift the same from the packet and also to engage with the adjusting screws for the purpose of 125 lifting the folders.

5. In a wrapping or packeting machine, the combination with means for feeding a par-

tially wrapped packet into the machine, of
folders adapted to coöperate with the end
folds of the wrapper to fold the same, a
paste magazine slidably mounted upon the
frame of the machine, a spring for forcing
said magazine in a direction to apply paste
to said packets, a reciprocating rod mounted
on the machine, and a cam on said rod for

moving the paste magazine away from the
packets. 10

In witness whereof I have hereunto set my
hand in presence of two witnesses.

CARL SIGFRID NYBERG.
